[57] CLAIM

The ornamental design for a plate or similar article, as shown and described.

DESCRIPTION

FIG. 1 is a top plan view of a plate or similar article showing my new design;

FIG. 2 is a bottom plan view thereof;

FIG. 3 is an end elevational view thereof;

FIG. 4 is a side elevational view thereof;

FIG. 5 is a cross-sectional view taken along line 5—5 of FIG. 1;

FIG. 6 is a cross-sectional view taken along line 6—6 of FIG. 1; and

FIG. 7 is an enlarged fragmentary sectional view of a portion of the rim of FIG. 6.

The characteristic feature of my design resides in the single row of beads incised into the upper surface of the rim between two continuous grooves in combination with the configuration of the plate or similar article as best shown in FIGS. 1, 6, and 7 on the drawing.

FIG. 1FIG. 5FIG. 2FIG. 3FIG. 7
